CLAIM

The ornamental design for a swimsuit, as shown and described.

DESCRIPTION

FIG. 1 is a front view of a swimsuit showing my new design.

FIG. 2 is a rear view thereof.

FIG. 3 is a left side view thereof; and,

FIG. 4 is a right side view thereof.

The broken lines illustrating portions of the swimsuit form no part of the claimed design. The broken lines illustrating a model are for environmental purposes only and form no part of the claimed design. The dot-dash broken lines define the bounds of the claimed design and form no part thereof.
